US00D659006S

(12) **United States Design Patent**
Wiescinski et al.

(10) **Patent No.:** **US D659,006 S**
(45) **Date of Patent:** ** *May 8, 2012

(54) **BOTTLE**

(75) Inventors: **Marc T. Wiescinski**, Chicago, IL (US);
Brent S. Nelson, Village of Lakewood,
IL (US)

(73) Assignee: **Tropicana Products, Inc.**, Bradenton,
FL (US)

(*) Notice: This patent is subject to a terminal disclaimer.

(**) Term: **14 Years**

(21) Appl. No.: **29/357,001**

(22) Filed: **Mar. 5, 2010**

(51) LOC (9) Cl. 09-01

(52) U.S. Cl. **D9/542**; D9/563

(57) **CLAIM**

The ornamental design for a bottle, as shown and described.

DESCRIPTION

FIG. 1 is a top, front, left perspective view of a bottle showing a first embodiment of our new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a bottom, front, left perspective view thereof;

FIG. 9 is a top, front, left perspective view of a bottle showing a second embodiment of our new design;

FIG. 10 is a front view thereof;

FIG. 11 is a right side view thereof;

FIG. 12 is a rear view thereof;

FIG. 13 is a left side view thereof;

FIG. 14 is a top view thereof;

FIG. 15 is a bottom view thereof; and,

FIG. 16 is a bottom, front, left perspective view thereof.

In the drawings, the dashed-dot-dashed broken lines represent unclaimed boundaries of the claimed design and the even length broken lines depict portions of the design that form no part of the claim.
